(57) **CLAIM**

The ornamental design for a tumbler and holder, as shown and described.

DESCRIPTION

FIG. 1 is a perspective view of a tumbler and holder showing our new design with the tumbler mounted in the holder; FIG. 2 is a front view of the tumbler and holder with tumbler mounted in the holder; FIG. 3 is a front view of the tumbler and holder with the tumbler dismounted from the holder; FIG. 4 is a left side view of the tumbler and holder with the tumbler mounted in the holder; and, FIG. 5 is a top view of the tumbler and holder with the tumbler mounted in the holder.

The front views (FIGS. 2 and 3) and rear views (not shown) of the tumbler and holder are symmetrical. Also, the left side view (FIG. 4) and right side view (not shown) of the tumbler and holder are symmetrical. The bottoms of the tumbler and holder are plain and unornamented. The surface shown in broken lines illustrates the environment in which the tumbler and holder are used. The surface shown in broken lines is provided for illustrative purposes only and forms no part of the claimed design. Lines are provided on the surfaces of the tumbler and holder to indicate surface shading.
